Primary Examiner — Prabhakar Deshmukh(74) *Attorney, Agent, or Firm* — Wilmer Cutler Pickering Hale & Dorr LLP.**CLAIM**

The ornamental design for a combined power module and cover for portable electronic devices, as shown and described.

DESCRIPTION

FIG. 1 is a top, front and left side perspective view of a combined power module and cover for portable electronic devices showing our new design;

FIG. 2 is a bottom, front and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines are included for the purpose of illustrating the environment and form no part of the claimed design.

The front view of all embodiments is the same as FIG. 3.
